UNITED STATES PATENT OFFICE.

FRANCIS McDOWELL, OF PHILADELPHIA, PENNSYLVANIA.

CAR-FENDER.

SPECIFICATION forming part of Letters Patent No. 544,742, dated August 20, 1895.

Application filed February 7, 1895. Serial No. 537,567. (No model.)

To all whom it may concern:

Be it known that I, FRANCIS McDOWELL, a citizen of the United States, residing at Philadelphia, in the county of Philadelphia and State of Pennsylvania, have invented certain new and useful Improvements in Car-Fenders, of which the following is a specification.

The invention relates to a car-fender combined with an automatic brake.

10 The object is to provide a car with a guard or fender adapted to be sustained normally out of operative position, and which on engaging an obstruction upon the track will become self-adjusting to serve as a wheel-guard, 15 and at the same time automatically set the brakes and thereby prevent serious accidents on street-railways.

With these objects in view the invention consists in the combination and arrangement 20 of parts hereinafter described and claimed.

In the accompanying drawings, forming part of this specification, in which similar letters of reference indicate similar parts in the several views, Figure 1 is a view in perspective of one embodiment of the invention applied. Fig. 2 is a plan view of the car-truck and the fender, showing the brake-operating mechanism. Fig. 3 is a vertical longitudinal sectional view. Fig. 4 is a cross-section on the 25 line 4-4 of Fig. 2. Fig. 5 is a similar view on the line 5-5 of Fig. 2. Fig. 6 is a detail view in perspective of the engaging-hanger for the trip-lever.

In the drawings, A designates the body of 30 a street-car, a the truck, and a² the platform thereof.

B designates the fender, which comprises a longitudinally-disposed tripping-bar b, pivotally supported beneath the car body and platform 35 and provided on one of its sides with an enlargement b². The inner end of this bar is loosely connected with the fender or wheel-guard, as will be described later on.

To the front of the car is pivotally attached 40 a swinging guard b³, having at its center an opening b⁴, through which the front end of the tripping-bar b is adapted to extend. Secured to the bottom of the car, between the swinging guard b³ and the pivot-point of the tripping-bar b, is a retaining-catch b⁵, having openings b⁶, through which the tripping-bar is adapted to pass, a rest or shoulder b⁷ being

formed in the opening, by which the tripping-bar is adapted to be held in operative position. Secured vertically movable in suitable guide- 55 ways is the fender proper b⁸, which consists, as seen in the drawings, of a cross-bar, to which is attached brooms or their equivalents, it being essential, however, that one or more downward-acting springs, such as b⁹, be secured to 60 the cross beam or support.

C designates the brake mechanism, consisting of a clutch having a fixed member c and a loose member c², each provided with engaging-teeth adapted to interlock. The loose 65 member c² is grooved at c³ to receive the forked end of a shifting-lever c⁴. A spring c⁵ is interposed between the loose member c² and the framework of the truck and serves to force the loose member toward the fixed member, 70 engagement being prevented, however, by the position of the lever c⁴, as will be described. To a suitable support attached to the car-body is pivoted this clutch operating or shifting lever, the front or free end of which 75 extends forward through a slot of a hanger c⁶, it being held about centrally of the slot, in which position the clutch members will be separated by a shoulder c⁷ of a rotatable spring trip-lock c⁸, from which an arm c⁹ extends forward beneath the inner end of the 80 trip-bar proper.

Beneath the car and between the axles of the wheel is located a cross-rod c¹⁰, to which chains are attached, and at their opposite 85 ends are secured to the brake-blocks or block-holders a chain c¹¹, being attached at one end to the loose member of the clutch and at its opposite end to the cross-rod.

The operation is as follows: Upon meeting 90 with an obstruction the guard will be pushed backward, and engaging the enlargement on the tripping-bar will cause the bar to be moved laterally a distance sufficient to release it from engagement with the shoulder b⁷ and 95 thereby allow the springs b⁹ to act and force the fender downward into position. The dropping of the trip-bar serves to release the clutch-operating lever and allow the spring c⁵ to act and throw the loose member into engagement with the fixed member, thereby 100 causing the chain to be wound on the drum of the loose member, and, rotating the cross-rod, apply the brakes. To avoid any danger of

the clutch breaking, the teeth are formed of a pitch of about forty-five degrees, and should the chain be wound too tight the loose member will pass a tooth, the spring c^5 allowing the loose member to be moved away from the fixed member upon undue strain being applied. To set the fender, the front end of the tripping-bar is lowered until it engages the shoulder b^7 , the other parts being actuated thereby and caused to assume proper position. By this construction it will be obvious that the fender will operate quickly, and should the object struck pass the guard the fender proper would prevent it from passing under the wheels of the car. At the same time that the guard is oscillated the rod to which are attached the brake-chains will be rotated and the brakes set by the rotating action of the front axle, making stoppage of the car almost instantaneous.

In the use of this fender upon electrically propelled cars it may be at times found convenient to interpose a switch in the main circuit, to be opened by the action of the tripping device in releasing the fender. It will

also be obvious that the motorman, by depressing the headed pin D which projects through an opening in the platform of the car, may at any time operate the trip to release the fender and thereby apply the brake. 30

Having thus described my invention, what I claim as new is—

The combination with a car, of a fender vertically movable in guides, a tripping-bar pivotally attached to the bottom of the car and connected at its rear end with the fender, a spring adapted to yieldingly retain the fender in a lowered position, a device for normally retaining the forward end of the tripping-bar depressed, means for releasing the bar, and 35 40 brake mechanism adapted to be actuated by the release of the bar, for the purpose described.

In testimony whereof I have hereunto affixed my signature in the presence of two 45 subscribing witnesses.

FRANCIS McDOWELL.
